UNITED STATES PATENT OFFICE.

ALFRED W. P. LIVESEY, OF BLACKHEATH, ENGLAND.

CHESS OR DRAUGHTS BOARD AND CHESS OR DRAUGHTS MAN.

SPECIFICATION forming part of Letters Patent No. 783,293, dated February 21, 1905.

Application filed February 3, 1904. Serial No. 191,907.

To all whom it may concern:

Be it known that I, ALFRED WILLIAM PERCY LIVESEY, a subject of the King of Great Britain, residing at 40 Bennett Park, Blackheath, county of Kent, England, have invented a new and useful Improvement in Chess or Draughts Boards and Chess or Draughts Men, of which the following is a full, clear, and exact description.

My invention has for its object the provision of chess and draught boards so manufactured that they can be doubled up or closed at any moment with the men standing in any position in which they may happen to be, so that in the case of an interrupted game the board can be reopened with all the men standing in the same position which they were in when the board was closed.

Reference is to be had to the accompanying drawings, forming a part of this specification, in which similar characters of reference indicate corresponding parts in all the views.

Figure 1 is a perspective view of a game-board constituting a preferred embodiment of my invention, showing the parts in extended position ready for use. Fig. 2 is a longitudinal sectional view thereof, showing the parts in partially-closed position. Fig. 3 is a plan view showing a modification which comes within the scope of my invention. Fig. 4 is a longitudinal sectional view on the line 4-4 of Fig. 3. Fig. 5 is a side elevation of a chess or draughts man constituting a portion of my invention. Fig. 6 is a similar view of another form of chess or draughts man, and Fig. 7 is a perspective view of another form of man which also comes within the scope of my invention.

In the form illustrated in Figs. 1 and 2 a board or support A is provided with a hinge B, running across the middle; but it will be obvious that this hinge may be placed at any other point upon the board. The board shown has upon each of the halves a series of rectangular tubes T, the number of which is made to correspond with the number of squares required for the particular game to be played. In the present instance four square tubes on each side of the hinge B are shown and one rectangular tube T' about half the size of one of the square tubes. The two rec-

tangular tubes, being next to the hinge and of the size mentioned, will together when the device is spread out, as shown in Fig. 1, constitute a substitute for an additional square tube, making nine in all. These rectangular and square tubes are preferably made of cardboard with hinged corners and are disposed parallel to the hinge, nearly touching each other when the parts are in an extended position. The squares on the chess-board or draught-board may be made on the top surface of these tubes, which will make a practically continuous surface.

As shown, the squares are in such position that the middle of each of the squares passes over divisions S between the pairs of tubes. All of the four corners of each of the tubes are pliable, so that when the board A is doubled up or closed in the ordinary way the two tubes T immediately contiguous to the hinge, pressing against one another, are flattened out in opposite directions, each of these tubes pressing in its turn against the next tube, and these latter against the next, and so on. All of the rectangular tubes are at the same time flattened out, and finally lie flat against the two halves of the base-boards A.

The marking of the squares can be done actually on the top surfaces of the tubes, as shown in Figs. 1 and 2. In that case the tubes should be held together by a convenient number of thin ribbons V of any suitable material, running across the tops of the tubes at right angles to the direction thereof and glued in position to each tube. For convenience these strips are so placed as to form the boundaries between each two adjacent squares or rows of squares, and one may be placed at each edge of the board, if desired. In the form shown in Figs. 3 and 4 the squares are marked on a sheet of leather L or other suitable material, which can be fastened bodily on the top surfaces of the tubes. In this case slits F are cut in the sheet in the middle of the square exactly over the divisions between the tubes. These slits are preferably about one-half the width of the squares and are provided for the insertion of the feet or prolongations of the chessmen and draughtsmen to be used.

It will be noticed that in the form shown in Fig. 1 the men are held merely by the two side surfaces of the contiguous tubes which come in the centers of the squares marked on 5 the tops of the tubes.

It will be obvious that as the boards are 10 swung outwardly from the closed or folded position through the position shown in Fig. 2 to that shown in Fig. 1, the tubes all being 15 connected together either by the tapes V or the leather or other covering L, all the tubes will gradually rise through a constantly-increasing angle until they stand erect.

The chessmen, draughtsmen, or other men 20 to be used for playing the game are cut in any desired shape or outline, the lower ends having a prolongation or foot which can be pushed down between two tubes in the space S, either 25 through the slits F or not, as the case may be. The men are consequently held erect by the contact with the surfaces of the rectangular tubes, as shown in Figs. 2 and 4.

Figs. 5, 6, and 7 represent these men, and 30 in these figures they are in the form of chessmen *m*, each having the foot or prolongation *p*. These three figures show different forms of men. In Fig. 5 a chessman is shown cut out in outline, so as to represent the vertical section of an ordinary solid chessman, while 35 in Fig. 6 the chessman is shown in such form as to represent the perspective outline of a similar solid chessman. These patterns will be either plane or shaded to represent the solid piece either on one or both sides.

Fig. 7 represents a pawn or an ordinary piece used in other games. These pawns consist of a flat disk *D*, of suitable material—as, for example, tin—which may be shaded on 40 both sides to represent a perspective view of a solid pawn or draughtsman and is provided with a narrow slit *H*, running part way across the center. Through this slit there passes at right angles a flat tapering piece *R* of the same or any desired material. This piece *R* is provided at about one-third of its length 45 from the broader end with two notches *h*, which fit in the substance of the disk *D* and hold the piece *R* with respect to the disk. The shoulders which form these notches are 50 designed to engage the two surfaces of the disk and prevent the piece *R* from slipping through the slot *H* under ordinary conditions. The slot *H* has to be sufficiently wide to allow the piece *R* to move freely in either direction until 55 it lies nearly flat against the disk *D*. When the narrow end of the piece *R* is pushed down between two tubes *T*, the disk *D* lies flat on a square of the board, and when the board is folded up the piece *R* is free to tilt over with 60 the tubes as they collapse, while the disk *D* remains flat upon the surface of the tube. The broad curved end of the piece *R* can be used as a handle for moving the draughtsmen from square to square. When a king is required, the draughtsman can be turned upside 65

down, so that the broad end can be pushed between the tube, leaving the narrow end projecting upwardly. This narrow end is preferably stamped with some designating word or character—as, for example, “king” or “queen”—so as to show for what the pawn has been substituted.

Having thus described my invention, what I claim as new, and desire to secure by Letters Patent, is—

1. A chess or draught board comprising a support with a hinge across the middle, rectangular tubes running across the board parallel to the direction of the hinge, five on each side of the hinge, the two contiguous to the hinge being of half the width of the others, a series of thin ribbons secured to the tops of the whole of the tubes for holding them together, and the four bends or corners of all the tubes being pliable, so that on doubling up or closing the board, the two tubes contiguous to the hinge press against one another, and this pressure being passed on from tube to tube, they are all at the same time forced down flat between the two halves of the board; 90 while on re-opening the board all the tubes are pulled up again to an upright position.

2. As a new article of manufacture, a game-piece comprising a disk having a slit therethrough, and a flat piece adapted to pass into 95 and rest in said slit.

3. A game-piece comprising a flat disk shaded to represent the perspective view of solid game-piece provided with a flat tapering piece of material passing through the 100 middle at right angles, but free to move in either direction so as to be able to lie practically flat against the disk; the longer end of this vertical piece being marked with a distinguishing mark.

4. A game-board comprising a support, and a series of tubes located thereon parallel to each other, said tubes having flexible corners and game-squares provided with means adapted to receive game-pieces, affixed to their upper 110 surfaces.

5. A game-board comprising a support, and a series of tubes located thereon parallel to each other, said tubes having squares thereon, and a slit in the interior of each square.

6. A game-board comprising a support, a series of parallel tubes located thereon, game-squares on said tubes, said squares having openings between each two adjacent tubes adapted to receive game-pieces.

7. A folding game-board comprising a support in two parts hinged together, and a series of rectangular tubes secured to the support parallel to the hinge, said tubes having flexible corners and having means adapted to receive game pieces.
